JESSE LYLE, OF DANVILLE, VIRGINIA, ASSIGNOR OF ONE-THIRD TO SAMUEL S. EPPER-
SON AND ONE-THIRD TO H. L. PRITCHETT, BOTH OF DANVILLE, VIRGINIA.

BUNCH-BUILDER ATTACHMENT.

1,260,414.

Specification of Letters Patent. Patented Mar. 26, 1918.

Application filed March 17, 1916. Serial No. 84,927.

To all whom it may concern:

Be it known that I, JESSE LYLE, a citizen of the United States, residing at Danville, in the county of Pittsylvania and State of 5 Virginia, have invented certain new and useful Improvements in Bunch-Builder Attachments, of which the following is a specification.

This invention relates to improvements in 10 bunch building attachments for spinning machines, and more particularly to the type disclosed in my Patent No. 1,149,930, dated August 10, 1915.

The object in view is the provision for 15 a more effective variation than heretofore secured in the length of traverse when changing from the bunch building traverse to the regular, normal traverse.

A further object is the attaining of 20 the first mentioned object by a minimum amount of mechanical alterations of the structure set forth in my above identified patent.

With these and further objects in view, 25 as will in part hereinafter be stated and in part become apparent, the invention comprises certain novel constructions, combinations and arrangements of parts as subsequently specified and claimed.

30 In the accompanying drawing:—

Figure 1 is a fragmentary side elevation of a part of a spinning machine embodying the features of the present invention.

Fig. 2 is an enlarged detail sectional elevation taken on the plane indicated by line 2, 2, of Fig. 1 and looking in the direction indicated by the arrow.

Fig. 3 is an enlarged detail fragmentary side elevation of the whirl and parts of its 40 chains deflected during the building of a bunch.

Fig. 4 is a similar view of the same with the parts in the position when the bunch is substantially completed and the full traverse is permitted.

Fig. 5 is an edge view of a whirl with the chains omitted.

Referring to the drawing by numerals, 1 indicates an ordinary spinning frame, having the usual supporting bars 2, 2, brackets 3, rock shaft 4 journaled therein, and rocker lever 5 carried by the rock shaft and provided with a counter balance weight 6 and the usual stroke stand 7, which may be 55 connected by a link 8 to a like stroke stand

not illustrated. The lever 5 has the usual rocker arm 9 sustaining and actuating the lifting rod 10, which engages and operates the ring rail 11, provided with the usual yarn guides for delivering yarn to the 60 bobbins 12.

A builder motion of the screw actuated let-off type is provided for actuating the stroke stand 7, and so far as the builder motion itself is concerned, it is of the ordinary form, as are all of the parts above described, the builder motion consisting of a swinging lever 13, counter balanced at 13', and actuated by a cam or other appropriate gear, not illustrated. Lever 13 is of usual 65 form and bears a rotatably mounted screw shaft 14, on which is threaded a traveling block 15. One end portion of screw 14 is engaged by the regular left-off mechanism of the builder motion, consisting of a 70 ratchet wheel 16 engaged by pawl 17, carried by the usual lever 18 pivoted to the outer end of shaft 14 and having a pivotal connection at 19 to the frame of the machine, so that as the lever 13 is successively 75 swung up and down, the pawl 17 will impart successive steps of rotation to the shaft 14, and thereby feed the block 15 along the lever 13. This provides for the regular gain 80 as will be apparent. The said block is engaged by a chain 20, which extends longitudinally of lever 13 and engages a whirl 21, journaled on the lever 13. A chain 20' is fixed to whirl 21 and extends upward 85 therefrom and is connected to the usual 90 whirl 22, journaled in the bracket 23, and in turn having its smaller cam or disk engaged by a chain 24 which extends to and is connected with the stroke stand 7, it being understood that the chain 20' engages 95 the larger disk or cam of whirl 22, whereby 100 in the ordinary operation of the structure described thus far, the successive strokes of the lever 13 will impart corresponding strokes to the lifting rod 10 and thence to 105 the ring rail 11, whereby the requisite traverse is afforded, while at the same time, the successive steps in the let-off of chain 20 due to the movement of block 15 along shaft 14 incident to the step by step rotation 110 of ratchet wheel 16, enables the stroke stand 7 to have successive gains which provides for the usual gain of the ring rail, whereby the ordinary form of winding for the several bobbins is provided, the traverse and gain 110

being maintained uniform throughout the building of the bobbin.

The automatic looms, however, as is now well known, are provided with feeler mechanism for actuating the bobbin ejecting and new bobbin supplying mechanism, and this feeler mechanism depends on its operation for the presence of a "bunch" substantially at the point of exhaustion of supply of yarn 10 on the bobbin. The mechanism described above without the details of whirl 21 and co-operating parts would not produce such a bunch, and various attempts have been made to provide mechanism which will produce a bunch, with more or less success, as, for example, the arrangement seen in my above identified patent. The present invention, however, provides a simple and more efficient means to this end.

20 The whirl 21 consists of two preferably integral peripheral grooved disks 21^a and 21^b, the former being of smaller diameter than the latter, and the chain 20 being wrapped part way about and fixed to the periphery of the disk 21^a while the chain 20' is wrapped part way about and fixed to the periphery of the disk 21^b. When the parts are in position for producing the full traverse for the ring rail, the chain 20' will 25 extend on a straight line upward from the periphery of disk 21^b, but at the beginning of each operation, before the parts reach this position, provision is made for deflecting the chain 20', so as to take up a portion 30 of the length of the chain and thus proportionally reduce the length of the stroke of the stand 7 and correspondingly take up the gain. To this end a lug 21^c is formed integral with or otherwise fixed to the periphery 35 of the disk 21^b and outstands at a tangent to such periphery. This lug upstands parallel to the chain 20' and does not interfere with or operatively engage the chain 20' except when the whirl 21 is oscillated, and 40 the whirl is not oscillated during the full traverse of the ring rail. At the beginning of the spinning operation, however, when it is desirable to have a very short traverse for the purpose of building a feeler bunch, the whirl 21 is oscillated with each swing 45 of the lever 13 so as to cause the free end of the lug 21^c to swing outward and into engagement with the chain 20' and to deflect the chain so as to take up the gain by taking up a portion of the effective stroke of lever 13. To accomplish this oscillation, it 50 is necessary to provide means for moving the chain 20 in advance of its let-off movement incident to rotation of shaft 14.

55 To this end, a tubular rod 25 is pivoted to a part of the frame-work, as for instance, to one of the bars 2 in position to depend toward the builder motion, and telescoped within rod 25 is a rod 26 whose lower end 60 is pivotally connected to the chain 20 as

by the pin fixed to the chain and passed through an eye 26' formed at the lower end of the rod 26. The upper or tubular rod may be pivotally mounted in any appropriate manner as by a pivot pin passed through an eye 25' at the upper end of the rod. The rod 25 is closed at its upper end, and arranged within the bore of rod 25 is a controlling section of rod 27, which is located to limit the inward thrust of rod 26 axially 70 of rod 25. To vary the distance of this thrust, the section 27 is provided with an axially arranged screw 28 adapted to be locked by a radial screw 29. By setting the screw 28 at any given point of longitudinal 75 adjustment, the abutting of the inner or upper end of rod 26 against the head of the screw 28 when the section 27 has its upper end resting against the closed end of rod 25, will positively limit the extent of inward or 80 upward thrust of rod 26.

In operation, when the block 15 is at its rearmost position and the ring rail 11 is starting its first stroke, the rod 26 will be given an upward thrust and will move within rod 25 until the control section 27 strikes the closed upper end of rod 25, or the equivalent of section 27 strikes this part, and thereupon, the rod 26 will enter no farther, and its protruding end with its pivotal engaging eye 26' will prevent the chain 20 from moving on up with the balance of the stroke of the builder motion so that only a small fragment of the otherwise delivered reciprocal movement of the chain is actually 90 delivered thereby. This interruption of chain 20 while the lever 13 continues to move upward, effects a relative movement of the chain 20 which rotates the whirl 21 in a direction for causing the lug 21^c to 95 swing outward and thus deflect the chain 20' and detract from the full effective movement which would otherwise be delivered through chain 20'. As explained in my above identified patent, the deflecting of 100 the chain 20 in itself would be sufficient for producing a curtailment in the movement of the stroke stand 7 sufficient for the building of a feeler bunch, but I find that the gain is not fully taken care of by the deflection of chain 20, and I have accordingly provided the lug 21^c which does effectively 105 take up the gain at the beginning of the operation and then gradually allows the gain to be felt at the ring rail. The ring 11 by the action of deflecting the chain 20 through the action of the rod 26 is given only a relatively short traverse in the same 110 length of time which would ordinarily be required to make the full traverse. The result is that the yarn which would ordinarily 115 be delivered for a full stroke of the ring rail, is delivered in a bunch, and it requires only two or three of such abbreviated strokes to develop the required feeler bunch. 120

It is to be observed that the pivot of rod 25 is so located that as the block 15 progresses along the shaft 14, and the chain 20 correspondingly progresses, the pivot engaging eye 26' moves away from the axial plane of the pivot of rod 25 so that after the first few strokes of the builder motion (enough to complete the required feeler bunch) the pivot engaging eye 26' will have moved sufficiently away from the axial plane of the pivot of rod 25 as to allow rod 25 and rod 26 to swing vertically to an extent permitting the chain 20 to remain straight, and whirl 21 will have moved angularly a distance sufficient to place lug 21° entirely out of range of engagement with chain 20'. Besides this, the whirl 21 ceases to oscillate as soon as chain 20 ceases to be deflected. The movement imparted by the chain 20' thus becomes and remains normal, and the traverse of the ring rail 11 accordingly becomes full and remains the same throughout the balance of the winding of the bobbins. The gain is, of course, proportionately affected since during the retardation incident to the deflection of chain 20 by rods 25 and 26, the effect of the operation of the let-off mechanism is practically nullified, and the bunch is built substantially without gain, whereas, as soon as the pivot of rod 26 moves to the position allowing the full operation of the builder motion, the gain becomes constant just the same as the traverse becomes constant.

It will be observed that in the course of operation of the structure described, the let-off caused by the movement of the block 15 and normally intended to provide for the regular gain will be taken up wholly at first by the thrust of the lug 21° deflecting the chain 20' but as the successive strokes of lever 13 causes the block 15 to progress down the shaft 14, the let-off of the chain 20 allows the whirl 21 to advance angularly in addition to its oscillating amount and, therefore, the lug 21° is gradually shifted away from the chain 20' while at the same time the actual amount of oscillation of whirl 21 is decreasing incident to the decrease in the amount of deflection of chain 20 throughout the successive strokes of lever 13 down to the point of no deflection. The result of this is that the action of the lug 21° is to first take up all of the gain and then to gradually allow the gain to be felt at the ring rail, so that the feeler bunch begins with a short traverse and no gain, and continues with a short traverse and a very slight gain and then gradually as it works into its full traverse also works into a full gain so that a feeler bunch is built which is destined to prevent sloughing off of the yarn as the bobbin approaches an exhausted condition which is an extremely desirable and advantageous condition as it

provides for the avoidance of loss by waste incident to a loosening of the yarn causing too abrupt building on a feeler bunch as has heretofore occurred.

What I claim is:—

1. The combination, with a spinning machine builder motion, of means for restricting the extent of effective movement of the initial strokes of the builder motion, and a whirl oscillated by said means and provided with means for taking up gain. 70

2. The combination, with a spinning machine builder motion, of a swinging rod and a rod telescoping therewith and connected with a portion of the builder motion for restricting the extent of effective movement of the initial strokes of the builder motion, and a whirl having a projection adapted to be oscillated incident to such restricting action for taking up gain. 80

3. The combination, with a spinning machine builder motion, of a swinging rod and a rod telescoping therewith and connected with the let-off chain of the builder motion for restricting the extent of effective movement of the initial strokes of a builder motion, and means actuated by the chain incident to such restriction for taking up gain. 90

4. The combination, with a spinning machine builder motion, of a swinging rod and a rod telescoping therewith and connected with the let-off chain of the builder motion for restricting the extent of effective movement of the initial strokes of the builder motion, and a whirl engaged by the chain and adapted to be oscillated incident to such restriction, the whirl being formed with means for taking up gain. 95

5. The combination, with a spinning machine builder motion, of a swinging rod and a rod telescoping therewith and connected with the let-off chain of the builder motion for restricting the extent of effective movement of the initial strokes of the builder motion for shortening the traverse, the builder motion having a stroke stand actuating the chain, and a whirl engaged by both of the chains and adapted to be oscillated by the former incident to such restriction, the said whirl having a projection disposed for engaging the second mentioned chain during the initial bunch building strokes of the builder motion for taking up gain. 105

6. The combination, with a spinning machine builder motion, of a swinging rod and a rod telescoping therewith and connected with the let-off chain of the builder motion for restricting the extent of effective movement of the initial strokes of the builder motion for shortening the traverse, the builder motion having a stroke stand actuating the chain, and a whirl engaged by both of the chains and adapted to be oscillated by the former incident to such restriction, the said whirl having a projection disposed for 115

engaging the second mentioned chain during the initial bunch building strokes of the builder motion for taking up gain, the said projection extending substantially at a tangent to the periphery of the whirl and adapted to outstand therefrom free from the second mentioned chain at the conclusion of the initial strokes.

7. The combination with a spinning machine frame, a builder motion therefor including means for causing a variable gain and means operable to counteract the last-mentioned means during initial operation of the builder motion, of means operably connected to the builder motion for restricting the extent of normal effective movement of the initial strokes to thereby operate the counteracting means.

8. The combination with a spinning machine frame, a builder motion therefor including means causing variable gain incident to operation of the builder motion, means carried by the builder motion for taking up gain during the initial bunch building strokes, of means supported by the frame and operably connected to the builder motion for restricting the extent of effective movement of the builder motion during the initial bunch building strokes to thereby cause a step by step shifting of the gain taking up means to progressively render the latter less effective.

9. The combination with a spinning machine frame, a builder motion therefor including means for causing variable gain incident to operation of the motion comprising a flexible connection, a device to which the flexible connection is attached having deflecting means for deflecting said connection to take up the gain during the initial strokes of the motion, of a second

deflecting means operably connected to said flexible connection for restricting the extent of effective movement of the builder motion to thereby cause actuation of the first mentioned deflecting means so that the latter becomes less effective as the operation of the motion continues.

10. The combination with a spinning machine frame, a builder motion therefor including means for causing variable gain incident to operation of the motion, a device for taking up gain during the initial bunch building strokes, of adjustable means swingingly connected at one end to the frame and operably connected to the builder motion at its other end to render said motion taking up means less effective, said last mentioned means being rendered inoperative incident to the operation of the means for causing variable gain whereby to render the gain taking up means inoperative.

11. The combination with a spinning machine frame, a builder motion therefor including a let-off chain and means intermittently operated for letting off said chain to produce a variable gain, a whirl for taking up gain during the initial bunch building strokes, and a swinging member connected to the frame at one end and to the let off chain at its other end for deflecting the let off chain to thereby variably actuate the whirl to render its deflecting means less effective as the operation of the builder motion continues.

In testimony whereof I affix my signature.

his
